UNITED STATES PATENT OFFICE.

FRANK PILLEY, OF KANSAS CITY, MISSOURI.

VALVE MECHANISM.

1,299,507.

Specification of Letters Patent.

Patented Apr. 8, 1919.

Application filed January 11, 1918 Serial No. 211,404.

To all whom it may concern:

Be it known that I, FRANK PILLEY, citizen of the United States, residing at Kansas City, in the county of Jackson and State 5 of Missouri, have invented certain new and useful Improvements in Valve Mechanism; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to automatic valves and more particularly to a valve of this character especially adapted for use in a machine for cleansing milk cans or the like; the principal object of the invention being 20 to provide a valve mechanism that may be opened and closed by contact of articles advanced through the machine, so that steam or other fluid will be discharged into the articles, to clean the same, as they move 25 past the valve, and the valve closed to shut off the fluid as the articles leave the valve position.

In accomplishing this object I have provided improved details of structure the preferred forms of which are illustrated in the accompanying drawings, wherein:

30 Figure I is a side view of a part of a can cleaning machine equipped with a valve constructed according to the present invention, showing a can in position to receive steam from the valve.

Fig. II is a transverse vertical section of the same.

Fig. III is an enlarged perspective view 40 of the valve mechanism.

Fig. IV is a transverse sectional view of the valve parts, particularly showing the discharge port of the stationary steam tube and its relation to the revoluble member.

45 Fig. V is a longitudinal, sectional view of the valve and its supporting members.

Referring more in detail to the drawings:

1-2 designate horizontally spaced, parallel guide ways forming a part of a can cleaning machine wherein the present valve is particularly adapted for use; the said guide-ways comprising base portions 3-3' and

upwardly and inwardly turned flanged portions 4-4' wherein the flared ends 5 of the 55 necks 6 of cans 7 may be slidably contained to retain the cans in an upturned position as they are advanced through the machine.

Extending transversely across the frame, are tie rods 8 whereby the guide rails are 60 held rigidly in spaced relation, and fixed thereon, parallel with the rails 1-2, are longitudinally extending rods or tubes 9-10 whereon the cans are supported as they are advanced along the guide ways. 65

Although it is not absolutely essential to the operation of the valve that a frame or machine of the character shown and described be used, the present structure is described in order to more clearly illustrate 70 the use and operation of the valve mechanism presently described.

The guide frame parts 1-2 and the supporting rods 9-10 are mounted by the cross or tie rods 8 above a vat or tank 11, 75 wherein the cans are drained, and mounted adjacent the upper edge of the tank is a steam supply pipe 12 having a leader 13 extended to a valve 14, embodying the present invention, from which steam is discharged into cans 7 as they are advanced in an inverted position along the guide frame. 80

The valve 14 in its preferred construction comprises a slightly tapered hub portion 15, provided at one end with an internally 85 threaded socket 16 into which the end of the leader supply pipe 13 is threaded, the opposite end of the hub having an extended shank 17, here shown fixed by a clamp 18 to the rail 2 to supplement the pipe 12 in supporting the valve in functional position. 90

Revolvibly fitted onto the hub 15 is a valve sleeve 19, which may be tightened onto the hub to prevent leakage and held in an adjusted position thereon by means of a centrally apertured cap 19' that incloses the shank 17 and is threaded onto the smaller end of the hub against a washer 17' that in turn seats against the adjacent end of the sleeve 19, the nut being provided at its outer face with sockets 19'' for receiving a wrench or other tool whereby it may be conveniently removed from the hub or tightened thereon. 95

Extending radially from the sleeve 19 are paired, oppositely extending arms 20-20' and 21-21' all of which are formed in,

tegrally with the sleeve 15 and are of sufficient length that they will extend into the path of the cans 7 advanced along the frames 1—2 and will be engaged by the advancing cans 5 to cause the sleeve to be revolved on the hub; the relative arrangement of the arms 20—20' and 21—21' is such that the opposite angles formed between the arms 20 and 21 and arms 20' and 21' are smaller than the adjacent angles between the arms, so that, on account of the hub of the valve being lower than the lower end of the can neck, a can moved against the arm 21 or 21' and into proper cleaning position will cause the arms 20 or 20' to assume a vertical position so that the cleaning fluid will be discharged directly into the can; the length of the arms 21—21' being dependent on the size of the can opening and the distance 15 the valve hub is spaced below the guideway.

In order that the succeeding movements of the valve sleeve may alternately close and open the valve so that it may operate effectively in its present adaptation, I provide 25 the arms 20—20' with discharge channels 22—22' which are adapted to move into and from registration at their inner ends with a discharge port 23 opening outwardly from the hub socket 16.

30 With the valve parts so constructed and assembled, and the valve mounted on the frame and connected with a steam pipe as here shown, the valve operates in the following manner: Assuming that the valve is closed and that the arm 21 extends vertically into the path of a can 7 being advanced along the guide ways 1—2, it is apparent that as the forward edge of the neck of the can engages the arm the sleeve will be revolved sufficiently to bring the channel of the arm 20 into communication with the discharge port of the hub 15 and steam will be discharged through the port into the can.

As the can continues to advance, the arm 20 45 is engaged by the rear wall of the can neck and the sleeve is again partially revolved to cover the port to prevent a further discharge of steam and to locate the arm 21' in such position that a following can will, by contact therewith, repeat the valve opening and closing operation just described.

It is apparent that a valve of this construction is operated automatically and in one direction under the control of the cans 55 or other articles passed thereover to both turn on and check the flow of steam therefrom and that steam is only discharged therefrom when the cans are in position to receive the entire amount and full effect 60 thereof.

It is further apparent that valves of this character may be used with various other machines and for other uses than that herein described, and that any desirable number of 65 discharge arms or channels may be provided

for the discharge of steam or other fluid used, without departing from the spirit of the invention.

Having thus described my invention, what I claim as new therein and desire to secure by Letters-Patent, is:—

1. In a machine of the character described, a valve comprising a fixed hub member provided at one end with a socket for receiving a fluid supply pipe and having a discharge port opening into the said socket, a sleeve revolvably mounted on the hub having channeled arms extending therefrom in the same plane and engageable by articles advanced through the machine to advance the sleeve to open and close communication between the supply pipe and arm channels.

2. In a machine of the character described, a valve comprising a fixed hub member provided at one end with a socket for receiving a fluid supply pipe and having a discharge port at one side opening into said socket, a sleeve revolvably mounted on the said hub having radially extending arms thereon all in the same plane and successively engageable by articles moved through the machine to effect partial rotation of the sleeve; the alternate arms being provided with discharge channels adapted to be moved successively into and from registration with the hub discharge port for the purpose set forth.

3. In a machine of the character described, a valve comprising a tapered hub member having a supporting shank at one end and provided at its opposite end with a socket for receiving a fluid supply pipe and having a discharge port at one side opening into said socket, a sleeve revolvably fitted onto the said hub having alternately arranged channeled and closed, radially extending arms thereon all in the same plane and successively engageable by articles advanced through the machine to intermittently, partially rotate the sleeve to move the channeled arms into and from communication with the hub discharge port and a cap threaded onto the smaller end of the hub to engage the sleeve and tighten the same about the hub.

4. A valve for washing machines, comprising a horizontal supporting hub member provided with a fluid inlet and a radial discharge opening, a sleeve rotatable on the hub member, and provided with radial arms, each alternate arm being channeled and having a port to register with the discharge opening and means for guiding articles to be washed into contact with an arm on the hub to rotate the sleeve to effect registration between the ports in the arms and the discharge port in the hub member.

5. A valve for washing machines, comprising a horizontally supporting conical hub member provided with a fluid inlet and a radial discharge opening, a sleeve rotatable 136

on the hub member and provided with radial arms, each alternate arm being channeled and having a port to register with the discharge opening, a cap threaded on the 5 smaller end of the hub member and adjustable against the sleeve to maintain the sleeve in close contact with the hub member and

means for guiding articles to be washed into contact with an arm on the sleeve, to rotate the sleeve to effect registration between the 10 ports in the arms and the discharge port in the hub member.

In testimony whereof I affix my signature.
FRANK PILLEY.
